UNITED STATES PATENT OFFICE.

JOSEPH OSTROSKY, JR., OF DURYEA, PENNSYLVANIA, AND PAUL OSTROSKY, OF DETROIT, MICHIGAN.

WINDOW FASTENER.

Application filed May 6, 1926. Serial No. 107,267.

This invention relates to window fasteners and more particularly to the ordinary cam fastener used to fasten a pair of sliding sashes.

5 The object of the invention is to provide means in a sash fastener for preventing the surreptitious opening of the fastener from the outside.

Another object of the invention is to provide 10 means for preventing the operation of the sash fastener from the outside, which may be easily and cheaply installed in the ordinary sash fastener.

Other objects and advantages will herein- 15 after appear.

An embodiment of the invention is illustrated in the accompanying drawing wherein:

Fig. 1 is a perspective view of the fastener.

Figure 2 is a sectional view thereof taken on the line 2—2 of Figure 1.

Figure 3 is a view similar to Figure 2 except that the position which the catch and fastener will assume when it is attempted to 25 unfasten the fastener is shown, and

Figure 4 is a detailed view of a slightly modified form.

The device comprises the usual base member 1, having the fastener 2 pivoted thereon at 3. The base is adapted to be secured to the top of a window sash by securing means passed through openings 4 arranged therein in the usual manner. The fastener 2 is provided with a handle 5 and an eccentric cam-shaped flange 6. The flange 6 is adapted to engage a keeper (not shown) secured to the bottom of a sash. The movement of the fastener in one direction is limited by a stop 7 pressed up from the top of the base. Heretofore it has been quite easy to open a fastener of the kind above described by simply inserting a putty or other knife or instrument between the sashes and forcing the fastener to rotate about its pivot to the unlatched position. In order to prevent such tampering, a safety catch 8 is provided. This catch 8 may take the form of an angular shaped arm having one end 9 thereof weighted and the other end provided with a lug 10. The catch is adapted to be pivoted intermediate its ends upon a pin 11. A slit 12 is formed in the front of the base 1 and toward the handle side of the fastener 2. 55 The catch 8 is inserted in this slit so that the

lug 10 will engage the under surface of the base 1 and the weighted end 9 will be in front of the base.

The pin 11 forming the pivot of the catch may be soldered to the front flange of the base. When in position, an end 13 of the catch will project above the base and be in the path of the fastener, thereby preventing movement of the fastener until the catch is raised. It will be apparent that all that is necessary to open the fastener is to raise the weighted end 9 of the catch and rotate the fastener in a counter-clockwise direction. So long as the fastener remains open, the corner 13 of the catch will be held depressed by the under surface thereof. When it is desired to fasten the windows, the fastener may be rotated in a clockwise direction in the usual manner, and as soon as the front edge thereof has become disengaged from the tip 13 the catch will swing about its pivot by gravity and thus prevent return movement of the fastener until the catch has again been manually raised.

In the modification shown in Figure 4, so lugs 14 are formed by bending inwardly the material of the base adjacent the slit 12. The catch may be pivoted between these lugs on a pivot 15 held in openings formed therein.

Having described in detail an embodiment of the invention, the following claims are herewith appended, it being distinctly understood that the invention is susceptible of various modifications and adaptations within the scope of the said claims.

What we claim is:

1. A window fastener comprising a base adapted to be mounted on one sash, a member rotatably mounted upon said base and adapted to engage a keeper arranged upon another sash when rotated in one direction, and a gravity actuated lever pivoted on said base to cause one end thereof to slidably engage the bottom of the rotatable member when the latter is disengaged from the keeper, said lever having a lug adapted to engage an edge of said rotatable member when the latter is engaged with its keeper to lock it in engagement position.

2. A window fastener comprising a base adapted to be secured to one sash, a member rotatably arranged upon said base and adapted to engage in one position, a keeper mounted upon another sash, and a gravity

actuated catch pivotally mounted in a slit formed in said base whereby said catch will prevent rotation of said member when in the keeper engaged position until said catch is manually raised.

3. A sash fastener comprising a base adapted to be mounted on one sash, a rotatable member arranged upon said base adapted to engage in one position a keeper mounted upon another sash, stop means arranged upon said base for limiting the movement of said member in one direction, and a gravity actuated catch pivotally arranged in a slit

formed in the front of said base for preventing movement of said member in the other direction, whereby said catch must be manually moved to swing said member out of engagement with the keeper, said catch being adapted to automatically move into operative position when said member is in keeper engaged position.

In testimony whereof we affix our signatures.

JOSEPH OSTROSKY, Jr.
PAUL OSTROSKY.
